(57) **CLAIM**

The ornamental design for a cutting insert, as shown and described.

DESCRIPTION

FIG. 1 is a perspective view of a first embodiment of the cutting insert;

FIG. 2 is a front view thereof;
FIG. 3 is a rear view thereof;
FIG. 4 is a left view thereof;
FIG. 5 is a right view thereof;
FIG. 6 is a top view thereof;
FIG. 7 is a bottom view thereof;
FIG. 8 is a detail view of the portion marked "8" in FIG. 2;
FIG. 9 is a detail view of the portion marked "9" in FIG. 2;
FIG. 10 is a detail view of the portion marked "10" in FIG. 6;
FIG. 11 is a detail view of the portion marked "11" in FIG. 6;
FIG. 12 is a cross-section along line "12-12" in FIG. 2;
FIG. 13 is a perspective view of a second embodiment of the cutting insert;
FIG. 14 is a front view thereof;
FIG. 15 is a rear view thereof;
FIG. 16 is a left view thereof;
FIG. 17 is a right view thereof;
FIG. 18 is a top view thereof;
FIG. 19 is a bottom view thereof;
FIG. 20 is a detail view of the portion marked "20" in FIG. 14;
FIG. 21 is a detail view of the portion marked "21" in FIG. 14;
FIG. 22 is a detail view of the portion marked "22" in FIG. 18;
FIG. 23 is a detail view of the portion marked "23" in FIG. 18; and,
FIG. 24 is a cross-section along line "24-24" in FIG. 14.
The evenly spaced broken lines depict unclaimed parts of the cutting insert and form no part of the claimed design. The single dot-dash chain lines depict a boundary of the claimed subject matter and form no part of the claimed design. The double dot-dash chain lines depict either (i) cross-sectional lines or (ii) areas shown as detail views in certain figures, and form no part of the claimed design.

1 Claim, 16 Drawing Sheets
